UNITED STATES PATENT OFFICE.

GEORGE R. McALLASTER, OF ROCHESTER, NEW YORK.

BED.

1,418,589.

Specification of Letters Patent. Patented June 6, 1922.

Application filed October 7, 1921. Serial No. 506,077.

To all whom it may concern:

Be it known that I, GEORGE R. McALLASTER, a citizen of the United States, and resident of Rochester, in the county of Monroe and State of New York, have invented 5 certain new and useful Improvements in Beds, of which the following is a specification.

The present invention relates to beds and 10 more particularly to the type in which a bed frame is mounted to swing on a support to a lowered and an upright position, an object of this invention being to provide a screening means which may be utilized for 15 screening the bed bottom when the latter is raised in an upright position, and for screening one side of the bed frame when the latter is in a lowered position. Another object of this invention is to provide a screening 20 means formed of a number of hingedly connected sections adapted to be arranged in a large variety of positions with reference to the bed frame so as to produce different screening effects.

25 To these and other ends, the invention consists of certain parts and combinations of parts all of which will be hereinafter described, the novel features being pointed out in the appended claims.

30 In the drawings:

Fig. 1 is a view in side elevation of an embodiment of the invention, parts being broken away;

35 Fig. 2 is a plan view of the base or support showing the manner in which the screening means is mounted thereon;

Fig. 3 shows the base or support with the screening means thereon adjusted to lie at one side of the base;

40 Fig. 4 is a diagrammatic view showing the bed frame in lowered position and the screening means lying at one side;

Fig. 5 is a diagrammatic view showing the bed frame in raised position and the screening 45 means covering the bottom and sides of the bed;

Fig. 6 is a view in elevation showing the screening means in front of the bed when the latter is in raised position;

50 Fig. 7 is a fragmentary plan view of another embodiment of the invention in which the screening means embodies a plurality of hingedly connected screening members;

Fig. 8 is a fragmentary view in elevation 55 of the embodiment shown in Fig. 7;

Fig. 9 is a diagrammatic view of the embodiment of the invention illustrated in Figs. 7 and 8, showing the bed frame in lowered position and the screening means folded at one side thereof; and

Fig. 10 is a diagrammatic view of the sections shown in Figs. 7 and 9, the bed frame being lowered and the screen member in position to screen the bed from the side.

In the embodiment of the invention illustrated in Figs. 1 to 6 there is provided a support comprising, in this instance, two base pieces 1 from each of which rises an upright 2, the uprights being connected by one or more cross pieces 3. The bed frame, 65 which may be of any suitable form, in this instance comprises side pieces 4 pivoted at 5 to the uprights 2 and connected by cross pieces 6 and 7, the latter being supported by frames 8 in spaced relation to the side pieces 4. A fabric 9 connects the cross pieces 6 and 7. The outer end of the frame may be supported by legs 10 pivoted at 11 to the side pieces 4 and connected by links 12 with the supports 2, 70 the links being pivoted at 13 to the legs 10 and at 14 to the supports. It follows that 75 this construction permits the bed frame to swing on the support to assume either a substantially horizontal position or substantially an upright position. None of the foregoing parts per se are claimed herein.

The feature of this invention is a screening means one form of which is illustrated in Figs. 1 to 6 inclusive, and another form of which is illustrated in Figs. 7 to 10, inclusive.

In the embodiment of the invention illustrated in Figs. 1 to 6, inclusive, the screen is in the form of a curtain or drapery 15 which is suspended from its upper edge by a frame comprising, in this instance, a central portion 16 and two end portions 17, the end portions being hinged at 18 to the central portion so that they may lie in alinement with the central portion or may be folded at 90 angles to the central portion. This frame is so mounted upon the bed that it may support the screen 15 in front of the bed when the latter is in an upright position, as shown in Figs. 1, 5 and 6, or the screen may lie to one side of the bed to hide such a bed from view when the bed is in lowered position, as shown in Fig. 4.

The supporting means for the screen supporting frame, in this instance, comprises 110

two members 19 and 20, the former having a vertical portion 21 turning in a bearing 2^a on either of the bed supporting members 2 about an upright axis and also having a main vertical portion 19 out of line with the portion 21 and pivotally connected to the vertical portion 22 of the member 20 at a point 23 which is eccentric to the turning axis of the support on the bed support. The member 20 turns in a socket 24 formed in a member 24^a slidably supported on the central portion 16 of the screen supporting frame and about a vertical axis which is out of line with the pivot 23 between the members 19 and 20. A brace 25 is pivotally connected at either 26 or 26^a, according to which side of the bed frame the screen is mounted, to the central portion 16 and has a perforated end 27 surrounding the member 20, an adjustable collar 28 being provided about the member 20 and below said perforated end portion 27 so that the outer end of the central portion 16, with the adjacent end portion 17, may be sustained in a horizontal plane and against sagging. The perforated end 27 permits the brace to swing on the member 20 and also permits the brace to be removed from the member 20 with the screen supporting frame members 16 and 17. The member 20 is connected with the member 19 in such manner that it may be separated therefrom, and the member 19 connects with either of the bed supports 2 so that it may be separated therefrom.

It is apparent that, in this embodiment, when the bed is in a lowered position the screen may be swung to one side of the bed, as shown in Fig. 4, the two pivotally connected members 19 and 20 permitting the screen to lie with its length parallel with the length of the bed. When the bed frame is in upright position, as shown in Figs. 5 and 6, the pivotally connected members 19 and 20 will permit the screen member to lie transversely of the length of the bed and the side pieces 17 may each be swung at an angle to the central portion 16 so as to cover the sides of the bed.

In the embodiment of the invention shown in Figs. 7 to 10, inclusive, the bed frame is the same as that shown in Figs. 1 to 6, inclusive, as is also the support for the bed frame. The member 19^a has a vertical portion 21^a turning in the bearing 2^a on the upright 2 about an upright axis. A member 20^a is U shaped in form and has one arm turning on the member 19^a, while the other arm is journaled in perforated lugs 24^a on the screen. The screen, in this embodiment of the invention, embodies a plurality of sections 15^a connected by hinges 15^b which are of well-known type of three leaves, the hinges being arranged in pairs and so disposed that adjacent sections may swing in either direction relatively to each other.

From the foregoing it will be seen that there has been provided a bed in which the bed frame may be hidden from view by a screening means when the bed frame is in a lowered or in an upright position. This screening means is so formed, that the appearance of the bed is destroyed when the latter is arranged in a room used for other purposes. The construction of the screening means is simple in operation and is readily moved to its different positions.

What I claim as my invention and desire to secure by Letters Patent is:

1. In combination with a support and a bed frame movable to a lowered and an upright position on the support, a screening means, and means movably connecting the screening means with the support to permit the screening means to move to one side of the bed frame when the latter is in a lowered position to hide said side of the bed, and to move it in front of the bed to cover the bottom of the bed frame when the latter is in an upright position.

2. In combination with a support and a bed frame movable to a lowered and an upright position on the support, a screening means, two members movably connecting said screening means with the support, one of said members being pivotally connected to the support about an upright axis and the other being pivotally connected to the screening means about an upright axis, the two members being pivotally connected to each other about an axis which is out of line with the pivotal connections of said members with the support and the screening means.

3. In combination with a support and a bed frame movable to a lowered and an upright position on the support, a screening means embodying a plurality of hinged members mounted to turn about an upright axis, and two members one pivotally connected to the support and the other pivotally connected to one of the hinged members of the screening means both about an upright axis, said two members also being pivotally connected to swing about an upright axis out of line with the pivotal connections of the support and the screening means.

4. In combination with a support and a bed frame movable to a lowered and an upright position on the support, a screening means embodying hinged members, and a drapery suspended from said members, and means connecting said screening members with the support embodying two members one of which is pivotally connected near its lower end to the support to turn about an upright axis and the other of which is pivotally connected to one of the hinged members of the screening means to turn about an upright axis, said two members being pivotally connected together to

turn about an upright axis out of line with and between the pivotal connections of said members with the support and the screening means.

5. In combination with a support and a bed frame movable to a lowered and an upright position on the support, a screening means embodying hingedly connected members, and a drapery suspended from said members, means connecting said screening members with the support embodying two members one of which is pivotally connected near its lower end to the support to turn about an upright axis and the other of 10 which is pivotally connected to one of the hinged members of the screening means to turn about an upright axis, said two members being pivotally connected together to turn about an upright axis out of line with 15 and between the pivotal connections of said members with the support and the screening means, and a brace pivotally connected to 20

one of the hinged members of the screening means and mounted to turn on the member to which said screening means is pivotally connected. 25

6. In combination with a support and a bed frame movable to a lowered and an upright position on the support, a screening means embodying three hinged members, a drapery suspended from said hinged members, a member having a vertical portion mounted to turn on the support about an upright axis, another member having a portion mounted to turn on the first named 30 member about an upright axis out of line with the axis about which the first named member turns on the support and having the central member of the screening means mounted to turn thereon about an axis out 35 of line with the axis about which such second member turns on the first named member. 40

GEORGE R. McALLASTER.
